UNITED STATES PATENT OFFICE.

HENRY PARKIN, OF ALBERT TERRACE BOW, AND CHARLES JAMES REYNOLDS, OF DOWNS PARK ROAD, CLAPTON, COUNTY OF MIDDLESEX, ENGLAND.

DOOR-LATCH.

SPECIFICATION forming part of Letters Patent No. 300,499, dated June 17, 1884.

Application filed December 4, 1883. (No model.) Patented in England May 8, 1883, No. 2,336; in France November 8, 1883, No. 158,430, and in Belgium November 19, 1883, No. 63,249.

To all whom it may concern:

Be it known that we, HENRY PARKIN, of Albert Terrace Bow, and CHARLES JAMES REYNOLDS, of Downs Park Road, Clapton, both 5 in the county of Middlesex, England, subjects of the Queen of Great Britain, have invented certain new and useful Improvements in Locks or Fastenings for Railway-Carriage and other Doors, (for which we have received 10 Letters Patent in Great Britain No. 2,336, dated May 8, 1883; in France, No. 158,430, dated November 8, 1883, and in Belgium, No. 63,249, dated November 19, 1883,) of which the following is a specification.

15 This invention has for its object improvements in locks or fastenings for railway-carriage and other doors.

We, according to our invention, construct a lock or fastening for a door with a sliding bolt, and with a catch carried upon the bolt, which retains the bolt in the unlocked position when the door is open, and these parts and the striking-plate are so arranged that in closing the door the catch is first released 25 by pressing back the bolt. The catch is then moved out of the way or disengaged, and, finally, the bolt is allowed to shoot forward behind the retaining-shoulder of the striking-plate. In opening the door the bolt is drawn 30 back by the handle, and the retaining-catch drops in before the bolt is clear of the striking-plate.

Figure 1 is a side view of a sliding-bolt or draw-latch lock of this construction, with the 35 latch or bolt in the position it occupies when the door is open. Fig. 2 is a section of the lock, showing the working parts. Fig. 3 is a side view of the striking-plate. Figs. 4 are sections of the same, taken on the lines 1 1 40 and 2 2; and Fig. 5 is a plan of the retaining-catch and spring.

In these figures, *h* is the lock-case; *i*, the 45 spring bolt or latch, which has a tail, *i'*. Its front end is sloped or rounded off where it rubs against the striking-plate, and it is shot forward by a flat coiled spring, *j*, surrounding the tail of the latch.

k is a retaining-catch, acted upon by a flat 50 spring, *l*, attached to it, and which bears against the cover-plate of the lock. *m* is a tumbler through which the handle-spindle passes. The spring-actuated retaining-catch

moves with the latch, and it serves to prevent the latch being shot forward, while the door is open, beyond the position it occupies 55 in Fig. 1. In this position farther outward movement of the latch is arrested by engagement of the retaining-catch with the lock-plate, the hooked end *k'* of the retaining-catch dropping into a hole, *h'*, formed in the lock-plate. To close the door no turn of the handle is needed. It is effected by a simple pressure on the door. The rounded or inclined 60 side of the latch first comes against an incline or curved surface, *n'*, on the striking-plate *n*, and forces the latch inward sufficiently to release the catch *k*. The outer end of the catch *k* then comes against a projection, *n''*, which lifts the hooked end clear from the hole in the case. Further movement of 70 the door allows the latch *i* to drop behind the incline *n'*. It then shoots forward to its full extent, and securely fastens the door. The releasing-catch moves with it, but the hook is kept from engaging with the hole in or 75 rubbing on the interior of the lock-case by its outer end resting against the projection at *n''*.

By constructing locks in the above way, so that the bolt has to be moved back a distance before its retaining-catch is turned or 80 moved into a position to set it out of action, undercut catches may be used, whereby a very secure hold is obtained, and yet, when the door is being closed, the catch can be turned or moved out of the way with the 85 greatest ease, and without the engaging surfaces being subjected to any wear or pressure.

Having thus described the nature of our said invention and the manner of performing the same, we would have it understood 90 that we claim—

The combination of the lock-case, the spring-bolt, the recessed striking-plate, the spring-actuated retaining-catch upon and reciprocating with the bolt, and means, substantially 95 such as described, for engaging the catch with the lock-plate, these members being and operating substantially as hereinbefore set forth.

HENRY PARKIN.

CHARLES JAMES REYNOLDS.
